WARNER R. BUXTON, OF LONGMEADOW, MASSACHUSETTS, ASSIGNOR TO BUXTON, INCORPORATED, OF SPRINGFIELD, MASSACHUSETTS, A CORPORATION OF MASSACHUSETTS

KEY CASE

Application filed September 8, 1930. Serial No. 480,391.

This invention relates to key cases and more particularly to the means for securing the key hooks in the case. The present improvement provides a ready interchangeability of the key hooks and at the same time a positive locking of the key hooks in the case, with an increase in the strength of the securing means as a whole. These and other and further objects will more specifically appear from the following specification and claims.

In the accompanying drawing, which illustrates one embodiment of the invention—

Fig. 1 is a front elevation of a key case, showing the improved fastening means, parts being broken away to show the structure;

Fig. 2 is a section on an enlarged scale substantially on line 2—2 of Fig. 1, the parts being in locked position;

Fig. 3 is a section similar to Fig. 2 but showing the parts in position for removal of the key hooks;

Fig. 4 is a fragmentary sectional plan view taken on the line 4—4 of Fig. 3;

Figs. 5 and 6 are plan views showing the blanks from which the outer and inner members, respectively, of the key fastening means are made;

Figs. 7 and 8 are top plan views showing the outer and inner members in partially assembled relation;

Fig. 9 is a view taken similarly to Fig. 1 and showing a modification; and

Fig. 10 is a view taken similarly to Fig. 2 and showing another modification.

Referring to the drawing, 10 designates the body of the case which may be of any desired form and to which the key hooks are secured. The hook fastening means com-

prises an inner member 11 in the form of a plate, one edge of which is bent into cylindrical form as at 12. Member 11 is secured to the case 10 in any suitable manner, as by rivets 9. The cylindrical portion 12 is cut out to form one or more transverse slots 13, one for each key hook 15, and the width of each slot is such as to permit free play of the shank 14 of a key hook 15. Each key hook is provided with a head 16 which is substan-

tially ball-shaped and of greater diameter

than the width of its slot 13. Each such slot is enlarged at 17, on the side of the cylindrical portion opposite the flat portion of member 11, to permit introduction of the head 16 into the interior of the cylindrical portion 12.

Positioned on inner member 11 is an outer member 19, also in the form of a plate, having one edge bent into a partial cylinder 20 of a diameter to be telescoped endwise on the inner member 11, as indicated in Figs. 7 and 8, and pivoted thereabout as shown in Figs. 2 and 3. Outer member 19 is provided with slots 21 coinciding with slots 13 and of substantially the same width. Slots 21

are enlarged at 22 sufficiently to admit the ball head 16 of a key hook. When the member 19 is rotated to the position shown in Fig. 3 openings 17 register with openings 22 and permit the insertion or removal of the head of a key hook.

When the parts are in their normal position, shown in Fig. 2, the openings 17 and 22 are out of registration and the key hooks are locked in, and against removal from, the inner cylinder, although each is free to be rotated about its own axis or to be swung to any position along its slot 13. Preferably the flat portion of outer member 19 is slightly longer than the flat portion of member 11, providing an over-

hanging edge 23 (Figs. 1 and 3) to facilitate raising the outer member into position for the insertion or removal of the key hooks. The arcuate length of the cylindrical portion 20 is such that when the openings 17 and 22

are in alignment its free edge 24 abuts the flat under face of member 11, as shown in Fig. 3, so that the unlocking position is at the limit of upward movement of member 19.

As will be apparent from Fig. 2, the head 16 of the key hook engages only the walls of the inner member 11, and that the weight, position, or manipulation of the keys have no tendency to move the outer member 19 from locking position. This tendency of the member 19 to rest inert, until intentionally manipulated, is aided by the leather of the key case bearing on the outer edge 24 of member 19, as shown in Fig. 2.

As an alternative or in addition to this ar-

55

95

100

angement for resisting relative movement of the members 12 and 20, these members may be so formed that, when interengaged, the one will press upon the other with a substantial friction hold sufficient to prevent unintentional relative turning movement. As shown in somewhat exaggerated form in Figs. 2 and 3, the surfaces of these members do not need to be truly cylindrical in their entirety. Particularly the end portions, as 25 and 26 of members 12 and 20, respectively, are not concentric with the remaining portions which are cylindrical. In consequence, when the member 20 is swung on member 12 from the position shown in Fig. 3 to that shown in Fig. 2, the portion 26 of member 20 will be caused to bear tightly against the cylindrical portion of member 12, while when the members occupy the relative positions shown in Fig. 3 there is no substantial amount of frictional engagement between them so that the member 20, after hooks 15 are removed, can be freely slid endwise on member 12.

25 The invention makes possible a stronger and more satisfactory construction of the supporting plate for the key holders 15. The plate 11 need no longer be formed with open ended slots, as formerly, but instead 30 slots 13, closed at both ends, as shown in Fig. 6, may be used. According to prior practice, open ended slots were used to enable the key holders 15 to be in place before the cylindrical portion, corresponding to 35 portion 12, was completely rolled into final form. This construction had the objection that the side walls of the slots might spread apart near the outer edge of the plate because of the lack of any connecting portion, 40 such as 27 in Fig. 6, to tie the walls together. With the present construction, spreading of the walls of the slots 13, as sometimes occurred in prior key cases due to a sidewise swinging of the keyholders (as from left to 45 right in Fig. 1) or other reasons, is prevented. Such spreading of the walls, of course, might result in the release of a hook 15 from the cylinder in which it is supposed to be confined. If, however, the old construction is used, (with open ended slots 13' 50 as shown in Fig. 10) spreading of these walls near the ends 28 would be prevented by the overlying member 19. Before the ends 28 could be sprung sidewise (in a direction axially of the cylinder 12') the side walls of 55 slots 21 in plate 19 would have to be spread, and this is resisted by the solid, unslotted, lower portion of plate 19.

60 As shown herein, the case proper, usually a leather folder such as 10, has an inside flap 10', and plate 11 is secured by rivets 9 to this part rather than directly to the outer part 10. This member 10' is stitched, as at 29, or otherwise secured to member 10 65 with freedom to move relatively thereto.

As shown, member 10' is stitched along one end edge only. This construction has an advantage where a plate such as 11 is used. The cylindrical portion 12 is offset toward the leather case 10 from the body of the 70 plate and tends to produce a bulge in the leather case. By the use of flap 10' or its equivalent much of the bulging is made to occur in the flap and inside the case where it doesn't show, as will be clear from Figs. 75 2 and 3, rather than in the folder 10 itself.

The ball head 16 is usually constructed by bending over one end of the shank 14 of the key holder. I may make this head slightly elliptical, as viewed in Fig. 4, so that it will not readily pass through the enlargements 17 and 22, when the hook is positioned as in Fig. 4 or as shown in full lines in Fig. 3. This tends to prevent all of the hooks falling out when the plate 19 is raised to the position shown in Fig. 3 because the major axis of the elliptical head is slightly greater than the diameter of hole 17. By lifting a hook 15 into the dotted line position shown in Fig. 3, the head 16 is turned so that the minor axis of its elliptical part is presented to hole 17 and, since such axis is slightly smaller than the diameter of the hole, the head 16 can be drawn through it.

55 In the modified form shown in Fig. 9 the outer member 19 is cut into a plurality of members 19', one for each key hook. The construction of the inner member 11 is exactly the same in the modified form as in the form previously described and the arrangement of the slots in both the outer and inner members is the same. The modified form has the advantage that one key hook 60 may be removed or inserted without disturbing the other keys and hooks in the case.

65 From the foregoing description the operation and advantages of the new structure will be generally apparent. There are some aspects of the invention that may be clearer through special mention. The form of the 70 invention as shown embodies the structure of a widely used key case with my improvements added. For example, the key case shown in Fig. 1, if the enlarged openings 17 in slots 13 and the part 19 were entirely omitted, would be in substantially the same form as key case structure which I have commercialized and which is now in wide use. In this form the side flaps of the case are buttoned in overlapping relation over the keys 75 on the hooks held in plate 11.

80 To embody my present invention I provide the enlarged points 17 at the top of slots 13, as seen in Fig. 1. In addition, I roll the plate 11 at the upper end into a cylinder 125 which is not quite tangent to the flat portion of plate 11. The slight off-set is shown as extending downwardly in Fig. 2 and has a particular purpose. It will be seen that the prior structure so far has been changed very 130

little. It will act exactly as heretofore except when a key hook 15 (one in each slot 13) is turned to vertical position that hook with its key can be taken out of the case. The ball end 16 of the hook can now pass through enlarged point 17 of the slot. There is a considerable advantage in thus removing the key with its hook from the key case. But such separation would be a real fault if it occurred accidentally. Such separation has occurred accidentally even without the provision of the enlarged point 17 in the slot 13. It has occurred upon the unintended spreading of a slot 13 far enough to let the hook head 16 pass through. Heretofore, the plate 11 has been formed with slots 13 open at one end, then the hooks 15 have been put on the plate and the cylinder 12 bent around from plate 11 until the end with the open slots 13 abuts the plate as at 28 in Fig. 10. But after manufacture in this convenient fashion the strains and pulls of the hooks and abuse of plate 11 have sometimes caused one or more slots 13 to open far enough to let the hooks slip out.

According to my present invention I provide the plate 19 with its cylindrical portion 20 to normally lock the hooks in plate 11 against the possibility of accidental separation which I have described. In the position of the parts shown in Fig. 2, each hook 15 may be operated to bring its key out of the case for use. Even if all the hooks with their keys are "flopped" out there is no drag by head 16 to turn plate 19, as heads 16 only contact plate 11 on the under side of the slots 13. When any head reaches enlargement 17 for contact with plate 19 such contact would only hold plate 19 in its normal position. Furthermore, the friction contact of the cylindrical portion 20 with the body of the case at point 24, and the friction of part 26 on member 12, give an additional tendency to hold plate 19 against unintentional turning.

No matter what the strains are with the plates 11 and 19 in the positions shown in Fig. 2 the key hooks cannot slip out unless the parts are broken. The former accidental enlargements at the ends of slots 13 are completely guarded against by plate 19. The cylindrical portion 20 with its slots 21 coinciding with slots 13 but with the enlarged points 22 of slots 21 offset with respect to the enlarged points 17 of slots 13 permits all the normal movements of the key hooks exactly as heretofore, but with the locked feature added. Except in the latter security, the key case is exactly what it was before the present invention, as plate 19 and cylinder 20 are normally an inert security means.

As an additional feature of my invention, I have provided plate 19 and plate 11 with means to enable the individual removal or replacement of the key hooks in a simple fashion, so that the ordinary user can readily

carry out the action. In my former key case structure, without the plate 19 it sometimes happened that the spring eye at the outer end of a key hook 15 would be opened up by abuse so as to let a key slip off the hook. The user might notice the chance for this by the distorted appearance of the hook but rather than buy a new key case he would take a chance and continue the use of his old one. Various means for replacing individual hooks have been heretofore proposed but so far as I know they have not gone into general use. By my present invention I have preserved all the advantages of the widely used key case and added the feature of means to remove or replace the hook in such a simple fashion as to be unobjectionable because it does not interfere with the common and ordinary use that has become customary in this kind of structure.

I show this feature particularly in Figs. 2 and 3, and it is clear that the user can lift plate 19 by inserting the finger under extension 23. The movement takes place until the end of the cylinder abuts the back of plate 11 at point 24. This is the position of the parts where enlarged point 22 of each slot 21 coincides with enlarged point 17 of each slot 13. Any key hook can be removed through these enlarged points 17 and 22 temporarily coinciding. A new hook may be inserted and the parts returned to the relative position of Fig. 2.

The simplicity of the means and the operation described has a special advantage in this respect. A user may use the same key case and more conveniently change keys than heretofore. It has been the habit of some users to put more than one key on a key hook. The overloading of the individual hooks has been one cause of the distortion by which a key sometimes slips off the hook. The users' habit is due in part to a tendency to use the key case for storing seldom used keys. Now, by rendering it much easier than it has been to take off and put on the case support an individual key, such keys can be separately stored and put in the key case only over the periods of need. It may seem that the key could be put on and taken off the hook 15 just as easily as to take the hook off the case and put on another. But this is not so because the hook 15 is made of very stiff spring metal and desirably so since the spring end with its hump resists to a considerable degree the entrance and exit of the key head. It is much simpler by my improved means to put a key and hook in the key case than to put the key on the hook. A user can by the new arrangement readily interchange hooks and keys from one key case to another or from a storage rack to and from a key case.

This facility of putting the key hook on the key case at any time gives a manufac-

turing advantage. In the key case I have been manufacturing the hooks are put in the supporting cylinder before the latter is formed. With my new arrangement I can form the entire key case and all its parts before the key hooks are assembled. Then I can telescopically slide plate 19, lift it into the position of Fig. 3, and put the hooks in then for the first time. As long as one hook is inserted plates 11 and 19 are locked against endwise movement. This makes for a better original assembly operation of the parts desired in the key case.

I have found from investigation that some people object to carrying their keys in the commonly used key case as compared to the ordinary key ring because the latter carries a very large number of keys or a small number and the over-all bulk varies directly with the number carried. The key case custom is to use cases of different sizes, as a 2, 4, 6, or 8 hook case. One of the ideas of the present invention is to make it so easy for the user to arrange his keys with my invention that he will use key cases either in a more convenient manner and under better practice than heretofore, or in the event that he has preferred to use key rings will now more readily change to key cases. As an example of improved practice for the individual user, a two-hook key case may carry his auto ignition and door lock or tire lock keys, a four-hook case may carry his home, office, desk, and safe keys, a six-hook case the next six most commonly used keys, and an eight-hook case the next eight most commonly used keys, and if he has more keys they are put in additional cases. Each of these key cases are of pocket size. Arranged in this order the user has all his keys in readily accessible form. But for the most part he does not want to carry on his person all his keys at all times. My new structure makes it exceedingly easy to slip out a desired key and hook without the slightest resistance from one case and interchange it with one from another key case. With this facility provided, the individual can and more readily will carry on his person only those keys needed. He will be less disposed to overload a single key case. He will not run the same liability of distorting his key case as he has sometimes heretofore by many unhooking and hooking-on operations of keys on the same key case. By the new arrangement he will find it about as easy to put the desired key on his key case as it is to put the same key in any other convenient resting place.

There are many phases of use in which the new structure is of definite advantage over prior structures in key cases. What has been said will indicate the fact that while the device of the improvement is simple, what it will accomplish is understood better from an analysis of its function in its various aspects

than a view of the mere mechanical form as shown in its preferred embodiment.

Having described my invention in its preferred form with one modification, I desire to claim it as broadly as the state of the prior art admits.

I claim:

1. A device for removably securing a key hook, having an enlarged head, in a key case which comprises tubular members positioned in telescopic relation, registering slots formed in said members, adapted to receive the shank of the key hook and of a width to permit free swivel movement and travel of the hook in the slots, enlarged openings communicating with said slots and positioned to be brought into registration for the introduction of the enlarged head of the key hook, by relative movement of the tubular members, and to be thereafter moved out of registration to lock the hooks in the slots. 75

2. A device for removably securing a key hook, having an enlarged head, in a key case which comprises an inner plate member having one edge bent into hollow cylindrical form and adapted to be secured to the body of a key case, an outer plate member having one edge bent around the cylindrical portion of the inner member to have a limited pivotal movement about the latter, registering slots formed in the cylindrical portions of said members adapted to receive the shank of the key hook and of a width to permit free swivel movement and travel of the hook in the slots, enlarged openings formed in the slots and positioned to be brought into registration for the introduction or removal of the enlarged head of the key hook when the plate members are rotated to the point of maximum separation, and to be moved out of registration to lock the hooks in the slots when the plates are moved towards each other. 100

3. A device for removably securing a key hook, having an enlarged head, in a key case which comprises an inner plate member having one edge bent into hollow cylindrical form and adapted to be secured to the body of a key case, an outer plate member having one edge bent around the cylindrical portion of the inner member to hinge the plate together, registering slots formed in the cylindrical portions of said members adapted to receive the shank of the key hook and of a width to permit free swivel movement and travel of the hook in the slots, the slot in the inner member opening to the free edge of the bent portion of said member and being bridged by the flat portion of the outer member when the flat portions of the inner and outer members are in contact, enlarged openings formed in the slots and positioned to be brought into registration for the introduction or removal of the enlarged head of the key hook and to be moved out of registration to prevent removal of said head at all other 115 120 125 130

points of pivotal movement of the plate members.

4. A device for removably securing a key hook, having an enlarged head, in a key case which comprises an inner plate member, adapted to be secured to the body of a key case and having one edge bent outwardly to form a hollow cylindrical portion, transverse slots formed in the cylindrically bent portion extending from the free edge of said portion to a point substantially diametrically opposite and terminating in an enlarged opening, said slots being adapted to receive the shanks of the key hooks and of a width to permit free 15 swivel movement and travel of the books in the slots, the enlarged terminal opening being of sufficient size to admit the enlarged head of the key hook, an outer plate positioned on the inner plate and having one edge bent around 20 the lower plate to hinge the plates together, the bent portion of the outer plate being of such extent that its free edge engages the flat portion of the inner plate when the outer plate is pivoted substantially 90° from the 25 lower plate, slots formed in the bent portion of the outer plate, said slots being of the same size and registering with the slots in the inner plate and extending from adjacent the free edge of the outer plate to the unbent portion 30 of the latter, said unbent portion bridging the open ends of the slots of the inner member when the plates are in contact, and an enlarged opening of sufficient size to admit the 35 enlarged head of the key hook formed in each slot in the outer member in position to register with the enlarged terminal openings in the inner member when the plates are positioned at their point of maximum separation.

5. A key case structure comprising, two 40 plates arranged for telescopic assembly, a set of slots arranged along each plate, means adapted to extend through said slots and support keys, each slot in each plate having an entrance for said means normally closed by 45 the other plate when the plates are assembled and lying one flat against the other, said plates having means by which they may be pivotally moved to uncover said entrances in both plates for the insertion or removal of 50 the key holding means, said first-named means by extending through said slots preventing relative endwise movement of said plates.

6. A key case comprising a foldable cover, 55 a supporting plate fastened along the top side of one cover panel, a cylindrical portion along the top side of said plate, said portion having a set of spaced slots transversely thereof from top to bottom, said slots having an enlarged 60 entrance only at the top side of the cylindrical portion, a cover plate movably mounted on and formed generally like the supporting plate and having corresponding slots but with the enlarged entrances thereto offset downwardly with respect to those in the support- 65

ing plate, whereby when the cover plate is lifted to make the entrance points of the slot coincide, key retaining members may be put in or removed from the slots, and key retaining members for said purpose. 70

7. A key case comprising a foldable cover, a supporting plate fastened along the top side of the cover panel, a cylindrical portion along the top side of said plate, said portion having a set of spaced slots transversely thereof from top to bottom, said slots having an enlarged entrance only at the top side of the cylindrical portion, a cover plate movably mounted on and formed generally like the supporting plate and having corresponding slots but with the enlarged entrances thereto offset downwardly with respect to those in the supporting plate, whereby when the cover plate is lifted to make the entrance points of the slot coincide, key retaining members may be put in or removed from the slots, key retaining members for said purpose, the cover plate having its lower edge overlapping the lower edge of the supporting plate so as to be readily lifted therefrom. 80

8. In a key case a foldable cover member, a stiff supporting plate fastened near the upper end of one cover panel, the edge of the plate being curled into a cylinder along its upper edge, a similar plate telescopically assembled to overlie the first plate and free to hinge on its underlying cylinder but not to be lifted out of telescopic registration therewith, a set of slots extending through both cylinders and normally in registration, each pair of slots having normally offset entrances thereto, said entrances positioned to be in alignment when the upper plate is pivotally moved about the lower plate so as to make a substantial angle with the cover panel and at all other times to be out of alignment, key retaining members which may be inserted and removed from the supporting plate only when the entrances to the slots are in alignment. 95

9. In a key case a cylindrical supporting member, a coaxially arranged cylindrical locking member having an open longitudinal portion to permit a limited rotary movement of the locking cylinder on the outside of the supporting member, each cylinder having a plate extension adapted to be brought into parallel contacting relation and into angular relation by said rotary movement, limited transverse slots in said cylinders arranged to coincide and having enlarged points arranged to be offset circumferentially of the cylinders when the plate extensions are parallel and at all times until the plates are manually separated through a substantial angle. 100

10. A key case structure, comprising, a plate having a slot therein closed at both ends and having one end including the slotted portion rolled into the form of a substantially cylindrical member with the axis thereof dis- 105

posed transversely to the slot, a key holder having a shank of a width to pass freely along the slot from end to end thereof and an enlarged head to lie within the cylindrical member, said slot having at one point an enlargement sufficient to allow said head to pass therethrough, a second and partly cylindrical member telescoped over the first member and turnable thereon, said second member 5 having a slot to coincide with the first named slot and an enlargement at one point in its slot to register with the first named enlargement when said members are relatively turned into one position, whereby the head 10 of the key holder may be passed through the registering enlargements and into or out of the interior of said first named member, said members being relatively turnable into another position wherein the enlargements are 15 moved out of registration and the head locked within the cylindrical member.

11. A key case structure, comprising, a plate having a slot therein closed at both ends and having one end including the slotted portion rolled into the form of a substantially cylindrical member with the axis thereof disposed transversely to the slot, a key holder having a shank of a width to pass freely along the slot from end to end thereof and an 20 enlarged head to lie within the cylindrical member, said slot having at one point an enlargement sufficient to allow said head to pass therethrough, a second and partly cylindrical member telescoped over the first member and turnable thereon, said second member 25 having a slot to coincide with the first named slot and an enlargement at one point in its slot to register with the first named enlargement when said members are relatively turned into one position, whereby the head of the key holder may be passed through the registering enlargements and into or out of the interior of said first named member, said members being relatively turnable into another 30 position wherein the enlargements are moved out of registration and the head locked within the cylindrical member, and means on one of said members cooperating with the other member to retain the engaged members in the last-named position.

12. In a key case a cylindrical supporting member, a coaxially arranged cylindrical locking member having an open longitudinal portion to permit a limited rotary movement 35 of the locking cylinder on the outside of the supporting member, each cylinder having a plate extension adapted to be brought into parallel contacting relation and into angular relation by said rotary movement, limited 40 transverse slots in said cylinders arranged to coincide and having enlarged points arranged to be offset circumferentially of the cylinders when the plate extensions are parallel and at all times until the plates are 45 manually separated through a substantial

angle, and means for creating a substantial friction between said members when said plate extensions are in parallel relation to resist relative turning movement thereof.

13. In a key case a cylindrical supporting member, a coaxially arranged cylindrical locking member having an open longitudinal portion to permit a limited rotary movement of the locking cylinder on the outside of the supporting member, each cylinder having a plate extension adapted to be brought into parallel contacting relation and into angular relation by said rotary movement, limited 70 transverse slots in said cylinders arranged to coincide and having enlarged points arranged to be offset circumferentially of the cylinders when the plate extensions are parallel and at all times until the plates are manually separated through a substantial angle, said members being freely slidable when the plate extensions are separated by a substantial angle, and means for creating a friction hold 75 between said members when the members are turned so that said extensions lie in parallel relation.

In testimony whereof I have affixed my signature:

WARNER R. BUXTON.
